UNITED STATES PATENT OFFICE.

RAYMOND A. HEISING, OF MILLBURN, NEW JERSEY, ASSIGNOR TO WESTERN ELECTRIC COMPANY, INCORPORATED, OF NEW YORK, N. Y., A CORPORATION OF NEW YORK.

FREQUENCY-GROUPING ARRANGEMENT FOR COMMUNICATION SYSTEMS.

Application filed December 31, 1923. Serial No. 682,631.

This invention relates to grouping of frequencies for radio transmitting and receiving and is particularly adapted for use in connection with systems in which the incoming waves are combined with transmitted waves to produce a beat frequency. More particularly the invention relates to wave length arrangements adapted to provide many two-way channels for ship-to-shore communication, the channels being arranged to provide minimum interference between channels.

An object of the invention is to provide for the utilization of a large number of frequencies suitable for radio communication in connection with systems of the type in which incoming waves and waves used in transmitting are combined to form a wave of intermediate frequency.

More specifically an object of this invention is to provide a grouped arrangement of frequencies for two-way communication with the frequencies in none of the groups overlapping.

In systems embodying the invention terminal stations may be provided in sets to utilize the wave lengths of each group. Thus if a particular group involves three pairs of wave lengths, these will serve for three simultaneous non-interfering two-way communications without interfering with conversations upon wave lengths of the other groups. The shore terminals for each group may comprise a group of channels of a multiplex system or a corresponding group of channels of individual systems located either close together or in the same general territory. In this specification individual systems will be disclosed specifically. The shore terminals of other groups of channels are preferably located in regions somewhat remote from each other. In the extreme case all the shore terminals of each group may be located at the same radio plant.

Although particularly adapted for ship-to-shore multiplex systems, the principles of the invention are applicable to other systems in which the terminal stations are either fixed or movable, or part fixed and part movable.

The individual systems which may be employed for carrying out the objects of the invention may each comprise a transmitting set and receiving set for each channel at each station. The transmitting set com-

prises a source of speech wave, amplifying devices, a source of high frequency waves, means for modulating the high frequency waves and an antenna for radiating the modulated waves. The receiving set comprises an antenna for receiving incoming waves, a plurality of detectors, a source of local oscillations, if such is necessary, and a receiver for receiving audible notes or speech waves.

A plurality of stations each with a different range of frequencies for transmitting and receiving are so located and are arranged to employ such frequencies as to prevent interference between stations. Each frequency may be utilized by a separate installation, or may be utilized in a separate channel of one installation. The beat frequency produced by the combination of the incoming waves and waves used in transmitting is different for each group of channels and the frequencies are so grouped that the combination of one used in transmitting by a ship station in one group with another used by a ship station for transmitting in a different group will produce a beat frequency unlike that of either of the two groups and consequently the undesired beat frequency will be tuned out by the receiving apparatus of the various channels of the two groups.

For a more definite explanation of the invention, reference is made to the accompanying drawings in which:

Fig. 1 represents a plurality of groups of pairs of frequencies for transmitting and receiving, each group having the pairs so arranged as to produce a beat frequency different from beat frequencies of other groups;

Fig. 2 represents a circuit diagram of a transmitting and receiving circuit constituting a single two-way channel;

Fig. 3 represents a transmitting and receiving circuit, the receiving circuit making use of locally produced oscillations for stepping down or beating down the beat frequency in case it is too high for selection by conveniently designed selective circuits; and

Fig. 4 is a diagrammatic representation of the relation of frequencies and geographical positioning in the system of the invention.

Fig. 1 represents six similar groups of

various pairs of frequencies arranged in accordance with this invention. In Group 1 the numbers to the left represent transmitting channels of 100, 110 and 120 kilocycles and those on the right represent respectively corresponding receiving channels of 125, 135 and 145 kilocycles. The combination of the corresponding transmitting and receiving frequency waves produce a beat frequency of 25 kilocycles, which may be detected and the resultant audible note received by telephone receivers. Any difference frequency beat produced by non-corresponding pairs of frequencies of Group 1 will be readily separable from a 25 kilocycle beat frequency. Group 2 is a group of channels transmitting frequencies ranging from 150 to 170 kilocycles inclusive, and receiving frequencies ranging from 180 to 200 kilocycles inclusive, with a beat frequency of 30 kilocycles. Group 3 comprises five channels with transmitting frequencies ranging from 210 to 250 kilocycles inclusive, and receiving frequencies from 260 to 300 kilocycles inclusive. For this group the beat frequency is 50 kilocycles. Group 4 contains six channels with frequencies ranging from 310 to 360 kilocycles inclusive, for transmitting, and 380 to 430 kilocycles inclusive, for receiving. In this group the beat frequency is 70 kilocycles. Group 5 has a beat frequency of 100 kilocycles and frequencies ranging from 440 to 530 kilocycles inclusive, for transmitting and 540 to 630 kilocycles inclusive for receiving. In Group 6 the frequencies range from 640 to 790 kilocycles inclusive, for transmitting, and from 800 to 950 kilocycles inclusive, for receiving. The beat frequency in this case is 160 kilocycles.

Fig. 4 discloses a typical frequency and geographical layout of the invention. The particular frequencies disclosed in this figure were, for convenience, made the same as those indicated in Fig. 1, only the frequencies of Groups 1, 2 and 3 actually being indicated by label. It is a particular purpose of this figure to show any relation of the frequency allocation to geographical distribution whereby there is made possible a compensation for a condition of frequency spacing which under other circumstances would be too small, by the device of a greater geographical spacing of the stations which, under these conditions, tend to interfere. The principle of this compensating operation will be explained in the later description of the operation of the invention.

Fig. 2 represents a transmitting and receiving system using two antennae and employing the method of combining waves of a transmitting frequency with the incoming waves to produce a beat frequency. Voice frequency waves are supplied to the voice frequency amplifying device 13 from the

circuit 18, which includes microphone 10 and source of direct current 11, by means of transformer 12. The microphone circuit typifies any source of low frequency or signaling waves such as a telephone line. Amplifying device 13 may be any of the conventional types, such as that disclosed by patent to Scriven, 1,459,419, June 19, 1923. High frequency carrier waves are supplied by a source 14 and are impressed upon a modulating device 15 along with amplified speech waves from amplifier 13. Modulator 15 may be of any well known type, such as that disclosed in the patent to Van der Bijl, 1,350,752, August 24, 1920. Modulated high frequency waves are supplied to the antenna circuit including the induction coil 16 and hence are radiated from aerial 17. Incoming waves are received by antenna 19 and pass through the induction coil 20 and capacity 21 to ground. Coil 20 is inductively coupled to coil 23 which with capacity 24 constitutes a tuned circuit 22 for selecting waves of the frequency to be detected. The incoming waves are impressed on the detector 25 along with waves of the carrier frequency wave used in transmitting and a resultant beat frequency wave is produced. Tuned circuit 26 comprising inductance 27 and capacity 28 and the tuned circuit 29 comprising inductance 30 and capacity 31 select the waves to be received. Such waves are then finally detected by the detector 32 and received by the receiver 33. Amplifying devices, if such are needed, may be supplied.

Fig. 3 represents a receiving system employing double detection to be used in a system involving this method of grouping frequencies. Transmitting is carried on in a manner similar to that shown in Fig. 2. Modulated waves from the source 34 are impressed upon the antenna 36 by means of induction coils 35 which act as a transformer. Incoming waves reach the antenna 37, pass through tuned circuit 38 comprising inductance 39 and capacity 40, through tuned circuit 41 which comprises inductance 42 and capacity 43, to ground. Coil 45 of tuned circuit 44 is inductively coupled to coil 42. Capacity 46 completes tuned circuit 44. Incoming waves and waves of the carrier frequency used in transmitting which are also received by the antenna 37 are impressed upon the high frequency detector 47 and a resultant beat frequency obtained. This beat frequency wave is selected by tuned circuit 48 made up of inductance 49 and capacity 50 and by the tuned circuit 64 made up of inductance 51 and capacity 54 and is transmitted to the intermediate frequency detector 55. Local oscillations to beat with the wave of the intermediate frequency are supplied to the intermediate frequency detector 55 by local oscillator 53 through in-

duction coils 51 and 52 which act as a secondary and primary of the transformer respectively. Waves of the intermediate frequency and locally generated oscillations are impressed upon the intermediate frequency detector and a second beat frequency obtained. Waves of this frequency are selected by the tuned circuit 56 comprising inductance 57 and capacity 58, and by circuit 59 comprising inductance 60 and capacity 61. These circuits are resonant at the beat frequency desired and select the waves for final detection. The waves are then impressed upon detector 62 and the resultant note received by the receiver 63 as in Fig. 2. If amplifying devices are needed such may be supplied at any point in the circuit.

Operation.

In operation, first considering Group 1 of Fig. 1, waves of frequencies of 100, 110 and 120 kilocycles are used for transmitting from a given station, while those of 125, 135 and 145 kilocycles are used for receiving at the same station. Transmitting wave frequencies may be used in connection with separate sets or may be the channels of one set. In either case they are usually located at a central point, which in ship-to-shore communication will be a land station. The waves of frequencies used in receiving will in this case be transmitted from ships at sea with which communication is carried on by a land station. In the absence of predetermined assignment of frequencies the shore station may signal the ship and indicate which frequency the ship is to use for transmission and reception. For example, the shore station will transmit over 100 kilocycles frequency and the ship over 125 kilocycles frequency. The incoming waves and the waves used in transmitting will be impressed simultaneously upon the detector 25 of such a receiving circuit as shown in Fig. 2. The beat frequency will be 25 kilocycles and will be selected by the tuned circuits 26 and 29 resonant at that frequency and impressed upon the detector 32 and the resultant audible note received by receiver 33. A ship station sending over the 125 kilocycle wave will have a beat note of 25 kilocycles when receiving, both with the station sending over the 100 kilocycle wave and the one sending over the 150 kilocycle wave of Group 2. By means of tuned circuit 22 the waves from the 150 kilocycle station can be tuned out and only the 100 kilocycle waves detected. The selective action of circuit 22 is facilitated by the fact that the shore stations of Group 2 will be spaced at some little distance from the shore stations of Group 1, hence when a ship is in the zone of the shore stations of Group 1, the energy of the 150 kilocycle wave from a station of Group 2, arriving at the ship will be relatively feeble.

The frequencies are grouped in such a manner that each group may represent a station located on different points along the coast for communication with ships, the larger groups being stations through which the greatest traffic passes. These stations will be located far enough apart to prevent interference with each other. In Groups 5 and 6 in which the beat frequency is 100 kilocycles and 160 kilocycles, it may be advisable to supply oscillations to beat with such beat frequencies. In this manner an intermediate frequency is produced, which can readily be selected from interfering wave components and detected. With reference to Fig. 3 incoming waves reach the antenna 37, pass through tuned circuits 38, 41 and 44 to the detector 47 where they are combined with waves of the carrier frequencies used in transmitting. The beat frequency obtained in this manner passes through tuned circuits 48 and 64 to the detector 55 along with oscillations from the local oscillator 53. The combination of the two waves produces a wave of intermediate frequency which is selected by tuned circuits 56 and 59, impressed upon detector 62 and the resultant note is received by receiver 63.

Each group has a beat frequency entirely different from the other groups, which facilitates selection of the proper messages for reasons hereinafter stated. Should a ship station sending over one frequency in one group receive a message sent by a ship station in a different group, the beat frequency between the two would be a frequency different from that of either of the two groups, and it would consequently be tuned out by the intermediate frequency tuned circuits provided for that purpose.

Consequently the present invention provides a multiplex ship-to-shore or other communication system in which a maximum number of channels can be operated with a minimum of interference. A high degree of selectivity results from the following features:

(1) Individual channels of one group of land stations employ such outgoing frequencies and such an intermediate frequency that undesired outgoing frequencies cannot produce beats of the intermediate frequency.

(2) Land stations of different groups which employ such outgoing frequencies that they might beat together to produce an intermediate frequency employed by either of said groups are so widely separated that high frequency selection is sufficient to prevent interference.

(3) Waves of frequencies outgoing from land stations of different groups or the same group arriving at a land station of still another group will be of energies so feeble that high frequency selection is sufficient to

prevent interference even though the frequencies differ by the intermediate frequency of land stations at which they arrive.

(4) Outgoing waves from two ship stations of any group or groups combining at a land station of any other group to produce waves of the intermediate frequency of that group will be of energy so feeble that high frequency selection will suffice.

(5) Waves of ship stations of the same group cannot produce waves of the intermediate frequency of that group. Within the group therefore both high and intermediate frequency selectivity will conspire to prevent interference.

(6) Waves outgoing from ship stations of the same or different groups arriving at any ship station having an intermediate frequency equal to the difference of the frequencies of the arriving waves will be so feeble that high frequency selectivity will suffice.

(7) Selectivity will be greatly increased by the fact that energy of the local outgoing carrier frequency at any station will in general be of much greater intensity than the energy of any wave arriving from a distant station. Waves of the desired incoming frequency will, therefore, be reinforced disproportionately to any reinforcement of undesired waves which may incidentally occur.

(8) In addition to the use of special separation, high frequency selectivity, and one or more stages of lower frequency selectivity, other known means such as directive transmission and receptive antenna may be employed in a manner and with effects well known.

The use of the grouping of frequencies and stations set forth herein is not limited in application to difference frequency or other duplex systems but may be employed in connection with other systems as will be apparent to those skilled in the art.

Furthermore the invention is not limited in application to frequency spacings of 10 kilocycles nor to the same frequency spacing of all the channels in each group or the same spacing or plan of spacing for the several groups.

In a typical system, for example, such as would cover the Atlantic seaboard of the United States the various groups of shore stations might be distributed at points along the coast such as Maine, Long Island, Delaware, Virginia, Florida and Texas. Each of these stations could be connected with the continental land line system and interconnected with each other to facilitate communication between any ship and any subscriber on land by a channel of a group of channels having termini nearest the ship.

The present invention is not limited in application to use with difference frequency duplex systems of any particular kind or to

use with circuits for transmission and reception of any specific nature, but is limited solely by the scope of the claims in which the features believed to be novel and patentable are set forth.

What is claimed is:

1. In a system for carrying on multiplex two-way communication by means of a certain range of wave frequencies in which the available frequency range is divided into groups, each group being composed of two portions each containing the same number of wave frequencies and comprising one or more pairs of two-way channels corresponding to the frequency groups, said groups being so physically related as to tend to interfere, means for transmitting a wave of one frequency from each portion in opposite directions to constitute a two-way channel, and means for receiving each said transmitted wave and combining it with the locally transmitted wave to produce a difference frequency wave, the difference between the frequencies of the pairs of waves for the two-way channels of each group being constant within each group, which constant amount differs for each group.

2. A radio system comprising apparatus for operating a plurality of groups of transmission channels, each group being located in a region more or less geographically distinct from the regions of the other groups but so related that waves from a channel of one group are incident on the receiving circuits of other groups, each group comprising one or more two-way channels each employing oppositely directed frequencies differing by a constant amount within the group, which constant amount differs for each group, the physical relation of the groups of channels being similar to the corresponding relation of their frequencies.

3. A system of radio stations having a plurality of two-way transmission channels with pairs of frequencies assigned to each two-way channel, each two-way channel comprising a receiving circuit of double selectivity, the frequencies of said pairs being arranged in consecutive groups each individual to a certain number of said pairs, the frequencies corresponding to each direction of transmission in said groups occupying a range individual thereto, said frequencies being assigned in such a manner, and the geographical spacing of the channels being such, that there is a relatively large frequency discrimination, both primary and secondary, against interfering waves originating at the nearest stations, and that the waves against which there is relatively small frequency discrimination, either primary or secondary, originate at more distant stations.

4. The system of claim 3 in which the spacing between the frequencies of a pair is

the same for all pairs in a group and different for different groups.

5. A radio system comprising a plurality of groups of one or more two-way channels, the one way channels of each group corresponding to each direction occupying an individual frequency range and constituting a half-group, the resultant series of half-groups in the frequency range as a whole being staggered with respect to the directions of transmission, each receiving circuit being of the double selective type comprising means for combining the incoming and outgoing waves to produce an intermediate frequency wave, the intermediate frequency being the same for all the two-way channels in a group, the minimum frequency difference between waves transmitted in the same direction in different groups differing from the closest intermediate frequency of a group by a less amount than the similar difference between waves transmitted in the same direction in said group, the frequency difference between each two oppositely directed one-way channels of each group differing from the intermediate frequency of an adjacent group by a less amount than the difference between the frequencies of adjacent one-way channels in either group, each half-group of receiving circuits being adapted to receive from the nearest half-group of transmitting circuits, and the physical relation of the groups of channels being similar to the corresponding relation of their frequencies.

30 6. A radio system comprising a plurality of groups of one or more two-way channels, the one-way channels of each group corresponding to each direction occupying an individual frequency range and constituting a half-group, the resultant series of half-groups in the frequency range as a whole being staggered with respect to the directions of transmission, each receiving circuit being of the double selective type comprising means for combining the incoming and outgoing waves to produce an intermediate frequency wave, the intermediate frequency being the same for all the two-way channels in a group, the physical relation of the groups of channels being similar to the corresponding relation of their frequencies, the frequency difference between each two oppositely directed one-way channels of each group differing from the intermediate frequency of an adjacent group by a less amount than the difference between the frequencies of adjacent one-way channels in either group, and each half-group of receiving circuits being adapted to receive from the nearest group of transmitting circuits.

55 7. A radio system comprising a plurality of groups of one or more two-way channels, the one-way channels of each group corresponding to each direction occupying an individual frequency range and constituting a half-

group, the resultant series of half-groups in the frequency range as a whole being staggered with respect to the directions of transmission, each receiving circuit being of the double selective type comprising means for combining the incoming and outgoing waves to produce an intermediate frequency wave, the intermediate frequency being the same for all the two-way channels in a group, the minimum frequency difference between waves transmitted in the same direction in different groups differing from the closest intermediate frequency of a group by a less amount than the similar difference between waves transmitted in the same direction in said group, the frequency difference between each two oppositely directed one-way channels of each group differing from the intermediate frequency of an adjacent group by a less amount than the difference between the frequencies of adjacent one-way channels in either group, each half-group of receiving circuits being adapted to receive from the nearest half-group of transmitting circuits, and the physical relation of the groups of channels being similar to the corresponding relation of their frequencies.

8. A radio system comprising a plurality of groups of one or more two-way channels, the one-way channels of each group corresponding to each direction occupying an individual frequency range and constituting a half-group, the resultant series of half-groups in the frequency range as a whole being staggered with respect to the directions of transmission, each receiving circuit being of a double-selective type comprising means for combining the incoming and outgoing waves to produce an intermediate frequency wave, the intermediate frequency being the same for all the two-way channels in a group, the minimum frequency difference, in the frequency arrangement as a whole, between waves transmitted in opposite directions and not belonging to a two-way channel, differing from the nearest intermediate frequency by a less amount than the similar difference between waves transmitted in the same direction in the group including said nearest intermediate frequency, each half-group of receiving circuits being adapted to receive from the nearest half-group of transmitting circuits and the physical relation of the groups of channels being similar to the corresponding relation of their frequencies.

In witness whereof, I hereunto subscribe my name this 28 day of December, A. D. 1923.

RAYMOND A. HEISING.
